COOLER FOR LIQUIDS

Alvin H. Baer, Carbondale, Pa., assignor to The
Carbondale Machine Company, Carbondale,
Pa., a corporation of Pennsylvania.

Application July 21, 1933, Serial No. 681,588

12 Claims. (Cl. 62—126)

My invention relates to a liquid cooler, herein shown as arranged for use as a brine cooler for an ice freezing tank. It may, however, be used for cooling any other liquid or fluid, such as water, oil, etc., in any of the various relations where such reduction of temperature may be found desirable. It is an object of my invention to provide a cooling device which is simple in construction and low in cost but in which a high efficiency is obtained.

The advantages of flooded refrigerant operation are well known to those skilled in the art but it has been difficult to combine efficient operation with low initial cost. Various arrangements have been suggested which require numerous welds in the pipes of the evaporator, or require heating of the pipes for bending them, or in which the upward incline or gradient of the parts of the pipes in the evaporator is not uniform or is insufficient for satisfactory operation. It is an object of my invention to do away with such unsatisfactory features by reducing the number of welds to a minimum while providing an approximately uniform gradient in all parts 25 of the coils for the easy release of gas formed therein.

Another object is to provide an arrangement of helical coils having this gradient but very easily constructed and when nested together will provide a large ratio of surface contact between the medium to be cooled and the pipes as compared to the total volume of such fluid passing the evaporator.

A further object of the invention is to provide coils of such a character as to permit baffles to be used in convenient and effective manner, whereby also to obviate the necessity for crowding pipes of peculiar shape close together.

Referring to the drawings, which are made a part of this application and in which similar reference characters indicate similar parts:

Fig. 1 is a side elevation of a preferred form of my invention, partly in section.

Fig. 2 is a horizontal section of the same, showing a part of the freezing tank with which my invention may be used, and.

Fig. 3 is a partial vertical section.

In the drawings, reference character 10 indicates a tank containing freezing cans 11 which may be arranged in any conventional or desirable manner. Adjacent one side of the tank there is a partition 12 separating the body of the tank from a race or a channel at 13, the partition terminating short of the ends of the tank 55 so that the channel is connected to the body

of the tank at both ends thereof. An agitator 14 which may be of any suitable or conventional character forces the brine of the tank through the race. It will be obvious that other means may be provided for propelling the fluid to be cooled through the channel and this fluid may come from any desired source instead of from a brine tank. In the present embodiment of the invention the agitator is driven by a pulley 15.

Within the race there is provided cooling means 65 in the form of an evaporator preferably, but not necessarily, utilizing vaporizable refrigerant for cooling the liquid passing through the race, the evaporator including a lower header 16 for each of a plurality of series of coils hereinafter described and an upper header 17 for each of said series. The lower headers are connected at one end to an inlet pipe 18 to which refrigerant is supplied from a surge drum 19, a pipe 20 serving to augment the supply of refrigerant as desired, 75 this pipe 20 being provided with a valve 21 for controlling such supply.

The upper headers are connected to an outlet pipe 22 leading to the surge drum 19, this surge drum serving the usual purpose of separating 80 liquid refrigerant from the gas rising from the evaporator so as to prevent the liquid from passing off through pipe 23 to the compressor. Conventional elements shown in connection with the surge drum include a supply pipe 24, a float 25 85 and a pipe 26 leading to the surge drum.

The evaporating or cooling coils interposed between the headers 16 and 17 may be referred to as units which are arranged in rows or series longitudinally and transversely of the race. A 90 unit comprises two or more helical or spirally wound pipes, i. e., an inner pipe 27 and an outer pipe 28. In the present embodiment of the invention the inner pipe 27 is a single wound coil and the outer pipe 28 may comprise a double wound 95 coil, i. e., two single coils 28, 28' wound with a wide pitch so that one may be turned into the other, the purpose being to keep the convolutions close together and to have approximately the same incline or gradient in all parts of all the pipes 100 of the unit. Obviously more than two coils may be included in the unit and in such case the third layer would be triple wound, etc. In this way a suitable incline for evacuation of the evaporated gas may be provided in very simple manner, since 105 the bending of helical pipes is a simple operation and this form of bent coil requires a minimum of welds while permitting the maintenance of a uniform and sufficient incline for the evaporated gas to pass off freely.

Preferably each unit or coil is provided at its open central portion with a baffle 29 which is preferably cylindrical and takes up the greater part of the open space in the coil. Baffles 30 are also provided in the spaces formed between sets of four coils as formed on account of the arrangement of the coils in rows transversely and longitudinally of the race, it being understood that any desirable number of longitudinal and transverse rows may be provided, such as will give the greatest efficiency under given circumstances. The cylindrical baffles 29 may be attached to the upper and lower headers and the cylindrical baffles 30 may be attached to the floor of the tank. Baffles of somewhat different form may obviously be used within the scope of my invention but cylindrical baffles are preferred, they being inexpensive and highly effective for the purpose of maintaining uniform velocity in the flow of liquid between the various turns of the inner and outer helical pipes in each nest, while the cylindrical baffles 30, guiding the liquid between the pipes, also increase the velocity of liquid flow between the coils and keep it uniform. It will be seen from the foregoing that I have provided an apparatus in which flooded refrigerant operation is accompanied by a high heat transfer rate while the cost of construction is low and the operation is highly efficient. The evaporator has been shown and described in connection with an ice-making system, though obviously it is not limited to such use. In the system herein shown, the tank 10 has a partition 31 extending from the partition 12 nearly to the other side, as usual, for directing the flow of brine in the tank. I have provided a door 32 in partition 31 adjacent to partition 12, which door is vertically slidable in guides 33, so that some of the brine may be short-circuited back to the agitator 14 without passing down between the cans.

It will be obvious to those skilled in the art that many changes may be made in my device all without departing from the spirit of the invention and therefore I do not limit myself to what is shown in the drawings and described in the specification, but only as indicated in the appended claims.

Having thus fully described my said invention, what I claim as new and desire to secure by Letters Patent is:

1. In a liquid cooler, a brine tank, a race connected at its ends to said tank, means for causing liquid to circulate from said tank through said race and back to the tank, an evaporator in said race comprising evaporating coils arranged in series along the race, each coil including nested concentric vertically arranged helical pipes of substantially similar gradient, upper and lower headers connected to said vertical pipes, a baffle extending through the center of each coil nest, and means for circulating vaporizable refrigerant through said evaporator.

2. In a liquid cooler, a race for liquid to be cooled, cooling coils comprising nested vertical helical pipes of substantially similar gradient, said coils being arranged in closely-spaced rows lengthwise and crosswise of said race, means for causing liquid to flow through said race, and baffles between the helical pipe nests.

3. A device as in claim 2, said baffles being each substantially tangent to the four adjacent coils.

4. In a fluid cooler, a race for fluid to be cooled,

upper and lower headers in said race, coils arranged in rows longitudinally and transversely of said race, said coils comprising helical pipes connected to the respective headers at their ends, a vertical baffle in each coil, and baffles in the spaces between sets of four coils.

5. In a fluid cooler, a race for fluid to be cooled, upper and lower headers in said race, a series of coils connected to the respective headers at their ends, said coils each comprising nested vertically arranged helical pipes, and a vertical baffle in each coil nest, the space between coils being open whereby liquid may flow crosswise past the coils in the race.

6. In a fluid cooler, a race for fluid to be cooled, upper and lower headers in said race, and a series of coils in said race, each coil comprising vertically arranged nested helical pipes providing helices of two or more diameters, said helices having substantially similar gradient, and being connected to the respective headers at their ends.

7. In a heat exchange device, a race for a fluid current, upper and lower headers in said race, and coils in said race connected to said headers, said coils including inner and outer helices with a greater number of spirally wound pipes in an outer helix than in an inner one, whereby substantially the same gradient may be preserved in all parts of said pipes.

8. In a liquid cooler, a race for liquid to be cooled, vertically extending cooling coils each having a plurality of nested, helical pipes with substantially similar upward gradient, said coils being arranged in closely-spaced rows lengthwise of said race, means for causing liquid to flow through said race transversely of said coils, and a baffle placed centrally within each nest of coils.

9. In an ice-making system, a tank, a partition therein providing a race communicating at spaced points with the tank, cooling means in the race, a partition extending from said first-named partition at a point between the ends of the race toward the opposite side of the tank, and a door in the second-named partition adjacent the first-named partition, whereby the liquid circulating through the tank and the race may be short-circuited back to the race.

10. In a heat exchange device, a race for a fluid, upper and lower headers in said race, vertically extending helical coils each connected to the respective headers, a baffle in each coil of such size as substantially to fill the central space therein, means for circulating a fluid in the race transversely of said coils, and means for circulating through the headers and coils a fluid of different temperature from that in the race.

11. In a heat exchange device, a coil comprising a plurality of nested helical pipes arranged about a vertical axis, inlet and outlet headers common to said pipes, a baffle concentric with said nested pipes, means for circulating a cooling medium through said pipes, and means for causing another fluid of different temperature to flow transversely of the axis of said coil.

12. In a heat exchange device, a coil comprising spirally wound pipes all having substantially the same gradient arranged in concentric helices of successively increasing diameter, one or more of said helices consisting of a plurality of such spirally wound pipes turned into each other so as to lie in a common cylindrical plane.

ALVIN H. BAER.
